S. NELSON

BAG HOLDER

Filed April 24, 1923

Inventor:
Swan Nelson.

By *Milof Stevens Co.*

Attorneys.

UNITED STATES PATENT OFFICE.

SWAN NELSON, OF CHICAGO, ILLINOIS.

BAG HOLDER.

Application filed April 24, 1923. Serial No. 634,372.

To all whom it may concern:

Be it known that I, SWAN NELSON, a citizen of the United States, residing at Chicago, in the county of Cook and State of Illinois, have invented new and useful Improvements in Bag Holders, of which the following is a specification.

This invention relates to bag holders, the invention having for its primary object the provision of a novel and improved device of the kind stated for holding bags while they are being filled and which may be used with bags of varying sizes.

Another important object of the invention is to provide a bag holder of the character set forth to which a bag may be quickly and conveniently applied, a simple and improved means being employed for spreading the mouth thereof.

The invention also has for an object to furnish a bag holder of this kind which is very simple in construction, strong and durable, and which may be cheaply manufactured.

With the above and other objects in view which will become more apparent as the description proceeds, the invention comprises such novel features of construction and arrangement of parts, and in order that the same may be better understood, reference is had to the accompanying drawings forming a part of this specification, wherein for the purpose of illustration the preferred embodiment of the invention has been disclosed, like reference characters being used throughout the several views to denote similar parts.

In the drawings,

Figure 1 is a perspective view of a bag holder embodying my invention, the position of a bag thereon being shown in dotted lines, and

Fig. 2 is a section on the line 2—2 of Fig. 1.

Figure 3 is a view similar to Figure 2 but with less of the pipe broken away.

Referring specifically to the drawings, numeral 5 denotes a plurality of pipe lengths forming the base of the device, the same being connected at their ends by elbows 6, which latter serve as feet to render the base more stable.

Intermediate the end of one of the pipe sections 5 is positioned a T coupling 7, the vertical branch of which receives the end of a tubular support 8, the same being inserted or otherwise secured within the T coupling

7. The tubular support 8 slidably receives at its upper end a rod 9, which latter carries the bag supporting means and is adapted for vertical adjustment in the tubular support 8 by means of an adjusting screw 10.

The supporting means for the bag comprises a U-shaped frame 12 which latter is mounted upon the end of the rod 9 by means of a coupling 11. The U-shaped frame 12 is tubular in cross-section and receives between its arms 13 the bag to be filled, each arm being provided adjacent its forward end with a hook 14 to which the bag is attached. The rear portions of each arm are formed with a longitudinal slot 15 in its lower surface for the reception of hooks 16 for engaging the back edge of the bag to be filled. Springs 17 carried by pins 18 within the arm serve to maintain the hooks 16 in the rearward end of their respective slots 15. Each arm 13 is provided with a lateral aperture 19 opposite the pin 18 to permit insertion of the coil spring 17. Spring 17 being flexible may be inserted through the slot 19 until the hooks 16 drop down through the slots 15, whereupon the eye at the end of the spring may be slipped over the pin 18. This construction makes ready removal of the springs for replacement as required.

From the foregoing description read in connection with the accompanying drawings, the structural details with their attendant advantages will be readily appreciated. The tubular support 8 receiving the rod 9 form an extensible support for the U-shaped member 12, thus adapting the device to be adjusted for bags of various heights, it being understood that the bag will be supported upon the floor, since this makes it unnecessary to construct a bag holder of such heavy materials as to adapt it for supporting the entire weight of the bag. In use the hooks 14 are caught in the front edge of the mouth of the bag, whereupon the hooks 16 will be pulled forward against the tension of the spring 17 to engage the rear edge of the bag mouth. When it is desired to remove the bag the rear hooks 16 will be disengaged whereupon the springs 17 will draw them back out of the way so that there is no danger of them catching in the bag after the hooks 14 have been disengaged and the bag removed. Another advantage of my construction is that the pipe lengths 5 with their connecting elbows 6 serve to form a ridge around the bottom of

the bag and tend to prevent any lateral movement of a partially filled bag, which movement might result in the disengagement of the hooks 14 and 16 from the mouth thereof. A base board 20 may be fitted between the pipe lengths forming the base if desired, thus assuring a smooth surface upon which the bag will rest and preventing catching or tearing of the bag as it is removed, it being understood that the pipe lengths will extend above the plane of said board for the purpose specified.

The tubes 8 and 9 may be removably fitted to the T-couplings 7 and 11 respectively in any preferred manner, such as by threading the same thereinto, so as to permit removal when the device is to be packed for shipment or stored away. The rods 8 and 9 having been removed from their respective T-couplings, the rod 9 may be slid into the rod 8 and clamped therein by means of the screw 10, thus economizing space and keeping the rods together so that they will be in a position for use when desired.

In accordance with the patent statutes I have illustrated my invention in concrete form and described it as constructed in a specified manner, yet it will be understood that I do not limit myself to the exact embodiment of the invention disclosed, as various changes and modifications therein will immediately suggest themselves to those skilled in the art, without departing from the spirit of my invention as defined by the following claim.

In summarizing it will be seen that the hooks 14 and 16 are arranged directly beneath and close to the spaced parallel sides

of the U-shaped bag supporting member so that the sides of the bag are arranged close to and directly beneath the tubular sides of the U-shaped supporting member whereby letters or other articles thrown toward the bag are not likely to lodge in the space between the bag and the spaced parallel sides 13 of the U-shaped supporting members. There is no space between the upper end of the bag and the spaced parallel side members of the U-shaped supporting member which would permit the passage of large articles.

Furthermore as the hooks 14 and 16 depend from the tubular members 13 they are not likely to be engaged by letters or other objects thrown toward the bag.

I claim:

A bag holder comprising a U-shaped member having spaced parallel tubular sides and a bight portion, a standard connected to the bight portion, said spaced parallel sides being provided with longitudinal slots in the lower sides thereof, springs anchored within said tubular sides and having bag engaging hooks extending through the slots and extending downwardly from beneath the spaced parallel sides, and fixed bag engaging hooks depending from beneath the spaced parallel sides, said first and second named hooks being directly beneath and close to said spaced parallel sides for supporting the sides of the engaged bag close to and directly beneath the sides of the U-shaped member.

In testimony whereof I affix my signature.

SWAN NELSON.
